UNITED STATES PATENT OFFICE.

JOSIAH SCOTT, OF TOLEDO, OHIO.

DOOR-CHECK.

1,273,937.

Specification of Letters Patent. Patented July 30, 1918.

Application filed June 30, 1916. Serial No. 106,798.

To all whom it may concern:

Be it known that I, JOSIAH SCOTT, a citizen of the United States, and a resident of Toledo, in the county of Lucas and State of

5 Ohio, have invented a certain new and useful Door-Check; and I do hereby declare the following to be a full, clear, and exact description of the invention, such as will enable others skilled in the art to which it 10 appertains to make and use the same, reference being had to the accompanying drawings, and to the characters of reference marked thereon, which form a part of this specification.

15 My invention relates to door checks and it particularly relates to a means for preventing the noise and injury of the slamming of doors—either glass doors, wooden doors or screen doors—particularly those that are 20 closed by the action of a spring.

The object of my invention is to overcome the defect commonly found in door checks, namely, that a cushion means is usually provided which holds the door from the door 25 jamb, preventing thereby tight closing of the door by the spring of the door. My invention provides a door check which permits the door to be tightly closed and which may be closed by a spring merely of sufficient strength to swing the door to the 30 jamb.

The invention may be contained in a number of forms of constructions and used for cushioning devices of different character. I 35 have selected a construction containing the invention as an example to show that the invention is practical and may be incorporated in a useful structure. The structure selected is illustrated in the accompanying drawings.

40 Figure 1 of the drawing illustrates broken sections of a door jamb and a door to which the construction embodying my invention is connected. Fig. 2 illustrates an end view of the door check. Fig. 3 illustrates the position of the check when the door is closed.

1 indicates the door casing, 2 is the door jamb and 3 is the door which is shown as open in Fig. 1 and as closed in Fig. 3. The 45 door check is secured to the jamb 2 and in position such that it may be acted upon by the door 3. It is supported in a housing 5 which may be provided with a downwardly extending lip 6. It is secured to the jamb 2 by means of screws 7 which pass through the lip 6 of the housing 5. The casing 5 is pro-

vided with two side walls 8, in each of which a diagonal slot 9 is cut. The cushion member 10, that is, the check itself, is supported by a cross bar 11 in the slots 9 of the side walls 8. The slots 9 are slightly larger than the cross bar 11 so as to allow movement of the bar 11 within the slot 9 and consequently limited movements of the cushion member 10. The lower end of the slot 9 is 60 provided with an angular portion 12 which extends substantially vertical when the check is secured to the door frame whereby is formed a hump or corner 13 in the angular side edges of the two portions of the 65 slot. The edge opposite the hump 13 in each slot may be rounded. The hump or corner of the angle is located about in a horizontal line passing through the center of the cross bar 11, or preferably slightly above it. The 70 hump in each slot gives sufficient resistance to movement of the cushion member 10 to cause the cushion member to turn when the end of the cushion member is pressed by the bar when the door is going comparatively 75 slow in its closing movement.

The cushion member 10 may be formed of any suitable material and the shape thereof may vary. In the form of the construction shown I have found that it is preferable to 80 make the cushion member 11 of rubber or rubber composition, or of similar material. It, however, may be formed of wood, having, if desired, cushion parts. If made of rubber one end of the cushion device will 85 cling to the surface of the door when it is brought toward the jamb with considerable force or swiftness and also it will cling to the end wall 20 of the casing when the door strikes it with sufficient impact to force the 90 cross bar 11 along the inclined slots 9. When, however, the door strikes it while moving toward the jamb slowly the door will turn the cushion member 10 without lifting the cross bar 11 from the angular 95 portions 12 of the slots 9. The cushion member may also be provided with a cam surface 21 which will operate to tilt the cushion member 10 within the casing 5 and cause it to assume a vertical position. This 100 will permit the door to close against the jamb by the action of its spring.

In the operation of the device the door when open will permit the cushion member 11 to assume the substantially horizontal 110 position indicated in Fig. 1. When, however, the door is allowed to slam to with

considerable speed it will knock the cross bar from the angular portions in the lower ends of the slots 9 and the nose 22 will cling to the surface of the door 3, and also 5 the corner or end 23 will cling to the rear wall 20 of the casing, which will bring the bar to a stop and will prevent it from striking against the jamb.

The door will be thrown back by reason 10 of the rebound from the cushion device 11 and will then return toward the jamb more slowly. Meantime the cross bar 11 will fall back into the angular portions 12 of the slots 9. The door pressing against the nose 15 20 will rock the cushion member 11 and be drawn to the jamb 2 by the action of its spring.

An adjustable stop 30 is located in the under wall or lip 31 for varying the tilt 20 of the cushion member 10 when the door is open to make certain the engagement of the cushion member with the door to prevent the door striking the jamb when it is moving swiftly toward the jamb.

Having thus described my invention, what 25 I claim as new, and desire to secure by Letters Patent, is—

1. In a door check, a casing having an angular slot, one portion of the slot extending substantially vertical and the other portion of the slot inclined away from the door, a door engaging member having a pivot pin located in the slot, the vertical portion of the slot adapted to permit rotary movement 30 of the door engaging member when the door is closed slowly and to shift to the inclined portion of the slot to permit engagement with the wall of the casing and the door.

when the door is closed quickly and to cause the return of the pin to the vertical portion 40 of the slot.

2. In a door check, a casing having an angular slot, an engaging member having a transverse pivot pin supported in the slot at the end thereof, the vertex of the angle 45 of the edge of the slot being located on the side of the pin away from the door to yieldingly resist the movement of the pin from one part of the slot to the other part of the slot.

3. In a door check, a casing having an angular slot, one portion of the slot being substantially vertical and the other portion of the slot extending rearwardly away from the door, and from the upper end of the other portion of the slot, an engaging member, a pivot pin for supporting the engaging member and extending through the slot, the movements of the pin and member being resisted by the angular edge of the slot away 55 from the door.

4. In a door check, a casing having an angular slot, a door engaging member extending from the casing, a pin for supporting the door engaging member and extending through the slot and adapted to rotate in one portion of the angular slot when the door is slowly closed and to engage the rear wall of the casing and the door when the pin is moved into the other portion of the slot by the rapid movement of the door, the movements of the pin in the slot being resisted by the angular edge of the slot.

In testimony whereof, I have hereunto signed my name to this specification.

JOSIAH SCOTT.
